S. F. KRAUS.
GAS JET REGULATOR.
APPLICATION FILED SEPT. 21, 1910.

1,088,825.

Patented Mar. 3, 1914.

UNITED STATES PATENT OFFICE.

SAMUEL F. KRAUS, OF DENVER, COLORADO, ASSIGNOR TO THE KRAUS LIGHT COMPANY, OF DENVER, COLORADO, A CORPORATION OF COLORADO.

GAS-JET REGULATOR.

1,088,825.

Specification of Letters Patent.

Patented Mar. 3, 1914.

Application filed September 21, 1910. Serial No. 583,131.

To all whom it may concern:

Be it known that I, SAMUEL F. KRAUS, a citizen of the United States, residing in the city and county of Denver and State of Colorado, have invented certain new and useful Improvements in Gas-Jet Regulators; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to improvements in regulators for gas burners, my object being to provide a device which when placed within the tube through which the supply of gas passes, may be adjusted to regulate the 20 size of the blaze or jet without throttling the supply or adjusting a cut-off valve for the purpose.

The main feature of my improved construction consists of a tube vertically disposed in the body of the burner, and whose upper extremity tapers inwardly and is slotted to form a number of yielding members, whereby when the tube is moved vertically with relation to a dome-shaped device surrounding the same and provided with a central opening, the spring members may be caused to approach each other, thus diminishing the cross sectional area of the gas exit. The outer portions of these spring 30 members extend vertically for a short distance from their upper ends, whereby they are adapted to protrude through the opening of the said dome, thus making it practicable, by the vertical adjustment of the dome or the 35 regulating tube or both, as the case may be, to control the jet of gas issuing from the opening in the dome within a considerable range.

Having briefly outlined my improved construction, I will proceed to describe the same in detail, reference being made to the accompanying drawing in which is illustrated an embodiment thereof.

In this drawing: Figure 1 is a vertical 50 longitudinal section of a gas burner equipped with my improved regulating device. Fig. 2 is a top plan view of the regulating device proper, or a view looking in

the direction of arrow 2, Fig. 1. Fig. 3 is a similar view showing the parts in different 55 relative positions, the dome being adjusted in this view to bring the vertical points of the regulating tube nearer together. Fig. 4 is a detail view of one form of the regulating tube or tip. Fig. 5 is a vertical longitudinal section similar to Fig. 1, showing, however, a slightly modified form of construction. Fig. 6 is a detail view of the form of regulating tube illustrated in Fig. 5.

The same reference characters indicate 65 the same parts in all the views.

Referring first more especially to Figs. 1 to 4 inclusive, let the numeral 5 designate a casing in which is inserted a valve plug 6 held in place by a coupling sleeve 7 threaded 70 on the lower extremity of the casing and having an inwardly extending flange 8 adapted to engage a shoulder 9 formed on the valve member, whereby the latter is supported in operative relation with the casing 75 and a conduit 10 through which the gas supply passes to the burner. This conduit as illustrated in the drawing is elbow-shaped and formed integral with the casing 5. The screw sleeve 7 is split on one side and provided with apertured lugs 12 adapted to receive a screw 12^A, whereby the sleeve may be caused to clamp the casing to which it is applied more or less tightly as may be desired. The valve piece 6 is slightly cone-shaped and fits within the counterpart opening formed in the casing 5, whereby as the valve piece becomes worn the screw sleeve 80 may be adjusted to raise the valve and cause it to maintain a tight fit. In the drawing, 85 however, the screw sleeve is shown at its limit of forward movement on the casing.

There is a passage 13 extending laterally through the horizontal member of the elbow 10 and through the wall of the casing with 90 which the said elbow is formed integral as heretofore explained. This passage is arranged to register with a port 14 formed in the valve piece when the valve is adjusted to allow the gas to enter the burner. As 95 illustrated in the drawing the valve piece is provided with a central recess 15 for the initial entrance of the gas. In the form of construction shown in the said views, the casing is open above the valve as shown at 105 16. The upper extremity of the casing is

reduced in size as shown at 17, and exteriorly threaded as shown at 18, to correspond with the interiorly threaded lower portion 19 of the dome 20, the latter being provided with a central opening 21 at its upper extremity. This dome is provided with an exteriorly toothed zone 22 to enable it to be readily rotated by hand, by simply passing the thumb and finger through openings 23 formed in the hood 24, which has reduced portions 25 and 26 at the top and bottom, its central portion 27 being enlarged, forming a relatively large chamber immediately surrounding the jet regulator; the openings 23 also serving to admit air freely to support combustion. The lower reduced part 26 of the hood rests upon a shoulder 28 formed on the casing 5.

My improved gas-jet-regulating tube 29 is inserted in the reduced upper extremity 17 of the casing and rests upon a shoulder 30 of the casing at the bottom of said reduced part 17. The lower part 31 of this tube is cylindrical in shape and fits closely within the opening of the casing part 17. The upper portion of the tube 29 is slotted as shown at 32 forming the tube into a number of yielding members 33, which taper inwardly as shown at 34 near the top of the tube, while their upper extremities 35 occupy a vertical position, whereby they are adapted to protrude through the opening 21 of the adjustable dome 20, and as the dome is moved downwardly, these members are compressed and their vertical extremities may be brought nearly in contact with each other, thus making it practicable to reduce the size of the issuing gas jet to a minimum degree without completely cutting off the same.

This is an important improvement over regulating tubes whose spring members are entirely confined within an outer tube, and in which the vertical points which protrude through the opening 21 are lacking.

In the form of construction shown in Figs. 5 and 6, the regulating tube is designated 36. In this form of construction the upper portion of the said tube is substantially the same as shown in the other views, the tube having the slots 36, the inwardly curved parts 34, and the vertical points 35, protruding through the opening 21 of the adjustable dome 20. This tube 36, however, extends downwardly into the chamber 16 above the valve piece 6, its lower extremity being closed as shown at 37, while above this closure inlet orifices 38 are formed to allow the gas to pass to the interior of the tube. The lower closed end 37 of this tube is provided with an interiorly threaded opening 39 in which is threaded the upper extremity of a rod 40. To this rod immediately below the closed end of the tube 36 is applied a lock nut 41. This rod 40 passes through the center of the valve piece 6, the latter being pro-

vided with a threaded opening 42 for the purpose. Attention is called to the fact that the adjustment of this form of construction, necessary for compressing the vertical points 35 for the purpose of diminishing the gas-exit opening through the top of the dome 20, as well as for releasing the said points to enlarge the gas-jet-issuing opening, may be accomplished either by turning the dome 20 upon the reduced threaded upper portion 17 of the casing or by turning the rod 40, since the lower extremity of the latter is exposed and equipped with a head 43 in which is formed a nick to receive a screw driver.

The valve piece 6 in both forms of construction protrudes below the screw sleeve 7. In the form of construction shown in Fig. 1 this valve may be turned for the purpose of cutting off the gas entering through the passage 13, by taking hold of the protruding lower extremity 44 of the valve piece with the thumb and finger, or by applying a suitable tool thereto, as may be desired. It will be observed that in both forms of construction the gas jet regulating tubes 29 and 36 are arranged coaxially with the valve for throttling the gas at the inlet of the burner. In order to rotate the valve 6 for this purpose in the form of construction shown in Fig. 5, the lower extremity of the valve protrudes and the latter may be turned either by the hand alone or by the use of a suitable tool. In this case, however, the rod 40 together with the regulating tube turn with the valve, but their relations to the other parts of the mechanism are not changed as will be readily understood, since the regulating tube and valve are coaxially arranged. In each form of construction the valve is provided with a stop pin 45 threaded into the valve piece and protruding into the lower slotted portion of the casing, the edges of the casing on opposite sides of the slot serving to limit the movement of the valve piece when the same is turned for the purpose of turning the gas out or cutting it off.

From the foregoing description the use and operation of my improved gas jet regulating device will be readily understood and need not be explained further in detail.

Having thus described my invention, what I claim is:

A gas jet regulating device comprising a casing, adapted to receive the supply of gas, a slotted tapering cylindrical tube inserted in the upper extremity of the casing, the slots of the tube forming the upper portion thereof into a number of spring members, the upper extremities of the spring members occupying approximately vertical positions and shaped to form a circular discharge orifice, and a dome-shaped device rotatably mounted on the casing and surrounding the spring members of the said

tube, the said dome-shaped device having a circular orifice at its upper extremity through which the vertical portion of the spring members protrude, the dome-shaped device being adjustable to regulate the circular discharge orifice of the tube, the vertical portions of the spring members being adapted to approach each other as the dome

is moved downwardly, for the purpose set forth.

In testimony whereof I affix my signature in presence of two witnesses.

SAMUEL F. KRAUS.
